US0D1073945S

(12) **United States Design Patent** (10) Patent No.: **US D1,073,945 S**
(45) Date of Patent: ** May 6, 2025

(54) **COIL FOR MEDICAL IMAGING APPARATUS**

(71) Applicant: **Siemens Healthineers AG**, Forchheim (DE)

(72) Inventors: **Stefanie Gügel-Wild**, Langensendelbach (DE); **Sebastian Dennert**, Lonnerstadt (DE)

(73) Assignee: **Siemens Healthineers AG**, Forchheim (DE)

(**) Term: **15 Years**

(21) Appl. No.: **29/940,418**

(22) Filed: **May 2, 2024**

Related U.S. Application Data

(62) Division of application No. 29/780,078, filed on Apr. 22, 2021.

(57) **CLAIM**

The ornamental design for a coil for medical imaging apparatus as shown and described.

DESCRIPTION

FIG. 1 is a front view of a coil for medical imaging apparatus showing our new design;

FIG. 2 is a back view thereof;

FIG. 3 is a top plan view thereof;

FIG. 4 is a bottom plan view thereof;

FIG. 5 is a left view thereof;

FIG. 6 is a right view thereof; and,

FIG. 7 is a perspective view thereof.

1 Claim, 7 Drawing Sheets
